ABSTRACT

A rotary fluid compressing displacing or expanding machine of the type in which lobes on a rotor rotate within a casing relative to blades which are rotatably mounted on the casing so as in sequence to form a barrier to the passage of fluid and by their rotation permit passing of the lobes to cause a continuous delivery of fluid in front of the lobes and intake of fluid behind the lobes. With the object of achieving a lower than usual noise level and an increased fluid displacement for a given casing diameter, an improved machine is characterized in that the tips of the blades sequentially form a sealing clearance with an inner surface of the casing which is concentric with the rotary axis and further in that the blade thickness to width ratio is in the range of $0.4/N$ to $0.9/N$ where N is the number of blades.

FIG. I

FIG. 2

ROTARY COMPRESSING, DISPLACING OR EXPANDING MACHINE

BACKGROUND OF THE INVENTION

The invention relates to rotary fluid compressing, displacing or expanding machines of the kind known as blade-type blowers and has been devised with the object of improving said machines by reducing their noise level and increasing the fluid displacement for a given casing diameter.

The specification of British Pat. No. 804,602 sets out the cycle of operation of this type of machine in which lobes mounted on a rotor rotate within a casing relative to blades which are rotatably mounted on the casing so as in sequence to form a barrier to the passage of air and by their rotation permit passing of the lobes to cause a continuous delivery of air in front of said lobes and intake of air behind said lobes.

In this type of blower there are three major sources of noise, due to:

1. the explosions of pockets of air carried over from the delivery space to the intake space.
2. Changes in velocity of the intake air due to variations in the effective area causing displacement with changes in rotor position.
3. The implosion of air from the delivery space to air trapped between the intake and delivery spaces.

Each of these excites air pressure fluctuations and thus, results in noise. The latter excites the mechanical vibration of the blade which resists the implosion.

Any part of the air circuit which forms a pipe amplifies noise when a pressure disturbance excites its natural frequency, and harmonics.

The only type of blade-type blower which does not give rise to condition (1) viz. pockets of air carried over from the delivery space to the intake space, has thin parallel sided blades. These offer a continuously changing projected area to the rotating lobes and since a varying rate of flow is created, therefore condition (2) exists. Further the thin blades offer little resistance to bending and so condition (3) is also a source of noise.

Most blowers have rotors comprising an end disc integral with inner and outer drums defining an annular channel within which the blades form a barrier. This revolves inside a stationary casing and thus, the full diameter of the machine is not useful working space. To utilize the space fully the blade tips should seal directly on the outer case. When this is done with the known type of blower, the recesses in the casing which maintain the seal over the blade spacing period form additional pockets of air to cause explosion noise.

In known types of this blower, when contact is made between the trapped air space and the delivery space the natural geometry of the structure causes a rapid increase in area of contact and thus, a large pressure wave enters the trapped volume exciting noise and blade vibration.

SUMMARY OF THE INVENTION

In accordance with the present invention, a fluid compressing, displacing or expanding machine of the type defined in paragraph 2 of this specification is characterized in that the tips of the blades sequentially form a sealing clearance with an inner surface of the casing which is concentric with the rotor axis and that the

blade thickness to width ratio is in the range of $0.4/N$ to $0.9/N$, where N is the number of blades.

The thickness of the blades is determined by the angle through which they turn over the period of the trapped volume and on the profile of the blade tip. The gap between the lobes has a width sufficient to pass the hub part of the blades and since the tips approach this gap at an angle, the thickness is not truly uniform but tapers with reducing thickness towards the outside diameter of the blade. The curvature of the blade may be approximate to the arc of the circle having a radius of $2d^2/t$, where D is the pitch circle diameter of the blades and t is the tip thickness thereof.

Some compensation can be made for the reduction in the sealing period resulting from the narrowing of the blade tips by not having these concentric with the blade center but made to a larger radius. This reduces the leakage gap at the beginning and end of the sealing period. The machine may thus have the tips of the blades made to a radius larger than half the blade width.

A low rate of pressure increase in the trapped volume is achieved by keeping it sealed from the intake space for a period and permitting a controlled rate of leakage from the delivery space to raise the pressure.

It may be arranged that such controlled leakage causes the start of compression.

Any rapid change of pressure on one side of a blade causes bending and vibration of the blade and its shaft; thus, noise is created. With the known cantilever blades this can be reduced by the use of blades which are thick at the supporting end.

The susceptibility of the blade to bending and vibrating also depends upon the method of mounting the blade. By use of a ring mounted on spacer pieces between the blades additional bearings can be mounted. This allows the blades to be doubly supported instead of cantilever supported.

The invention thus may further provide for the blades to be supported at both ends.

When ports are cut in a rotor for the passing of the air, the flow loss through them sets an economic limit to the speed of operation. Also, the distance from the port to the blade which forms the end of the working space associated with that port creates a pipe length in which air pressure waves create noise.

Both these conditions can be avoided by eliminating the end disc of the rotor and having a rotor in the form of a bar having to one side of its rotation axis radially inner and outer lobes and to the opposite side of its rotation axis a plate which makes sealing clearance with the end of the blade which forms the barrier to the passage of fluid. Further, a duct which rotates with the rotor may separate the intake and delivery air flows. By this means the area available for the passage of air at the sides of the rotor is greater than the effective pressure applying area of the lobes and thus, there is no restriction to flow where the air passes the plane of the rotor.

BRIEF DESCRIPTION OF THE DRAWING

A particular and at present preferred improved blower in accordance with the invention is hereinafter described by way of example with reference to the drawing which accompanied the specification, wherein:

FIG. 1 is a transverse section of the blower and the working space swept by the lobes, and

FIG. 2 is a longitudinal section on the line XYZ of FIG. 1, showing the air ducting and blade mounting.

DETAILED DESCRIPTION OF THE PREFERRED EMBODIMENT

The blower of FIGS. 1 and 2 comprises a cylindrical casing 1 in which runs concentrically a bar or 'anchor' type rotor comprising an inner sealing hub 2 and a radial bar 3 which support a radially outer lobe 4, a radially inner lobe 5, and the radially inner and radially outer sealing plates 6 and 7 which seal the ends of the blades 8 when they contain between them the 'trapped air volume' of a working space 9. The thickness of these blades is such that there is always an effective seal on the bore of the casing between a delivery space 10 and an intake space 11. In order to pass between the lobes 4 and 5 with a constant clearance at the various angles of rotation the thickness of the blades is reduced from the parallel towards the ends. A curve having a radius of $2 \times$ blade pitch circle diameter squared/blade-thickness is satisfactory, but within normal limits of clearance an approximation of this shape may be made up of flat planes.

A continuous seal must be obtained between the delivery and intake spaces at the lobes, and where the lobes pass from one blade tip to the next, concentric stationary spacing pieces 12 are used to fill the gaps between the blade tips.

The sealing plates 6 and 7 are preferably made to cover a larger arc than the trapped air volume 9. This gives a period of time over which compression takes place. The rate of compression is controlled by the leakage around the blade on the delivery side and the rotor hub may be cut away at 13 to give the requisite leakage flow rate. It is more convenient however to have groove holes formed in the sealing plates 6 and 7 to yield this controlled increase in leakage compression.

In FIG. 2 there is shown a ring 14 mounted on the spacing pieces 12 and which supports the blades 8 at their ends remote from the backplate 15. Further, the ring 14 runs in close fitting grooves between the lobes 4 and 5 and the two parts of the sealing plates 6 and 7. The air intake from the casing 16 to the working space 11 is via a rotating duct 17 which maintains an air seal between the casing 16 and the casing 1. The air is delivered from the working space 10 to a delivery casing 18 round the outside of this rotating duct and thence to a delivery flange 19.

The design as described satisfies the object of the invention and provides a machine having a minimum of sources of noise in that:

1. There are no pockets of air carried over from the delivery to the intake space;
2. The effective area causing displacement remains substantially constant. Also, the projected area of the rotating lobes remains constant so that if the projected area of the blades were also constant then the air flow into the machine would be steady. By choosing a blade having a tip thickness t and diameter d to give a t/d ratio within the range of $1.4/N$ to $0.9/N$ where N is the number of blades and by suitable choice of the blade tip radius it is arranged that the projected area of the outer half of the blade does remain substantially constant. At

the center hub the effective area causing displacement is low and small changes in projected area of the blades are acceptable because they cause little change in rate of the total air intake.

3. The implosion of air from the delivery space to the trapped volume is brought to a low level of intensity by making it take place over a long time period. The rate of leakage is controlled by profiling one of the rotating surfaces which makes a seal on the blade, as depicted by the cut away part 13. To avoid too rapid an increase in leakage area, the blade tips tend to seal again towards the end of the part 13 to compensate for the rapid increase in leakage area at the outer blade tip. The leakage compression period can be made equal to one quarter of the blade separation angle or cyclic repeat time which in the machine of FIG. 1 is 90° or four cycles per revolution and the compression period 22.5° . The pressure rise in the trapped volume although a little faster than that given by a piston in a cylinder is slower than the so-called 'back flow' compression of the Roots type blower. The trapping blade is subject to this rising pressure on one side and inlet pressure on the other. This causes bending of the blade and it is a feature of the design that the natural frequency of bending of the blade is high compared with the frequency of blade loading by compression pressure. It is to assist in achieving this feature that the blade is supported at both ends by the ring 14 as previously explained instead of by a cantilever arrangement.

Air pressure disturbance can be reduced, but not eliminated. Eddy noises of air passing through the working clearances remain, even with steady flow. It is possible however, to reduce the amplification given to such noises, and other pressure changes, by not letting them excite air vibrations in pipes.

The working spaces within the machine become definable as pipes whenever a port causes a restriction and so define a length from this restriction to the closed end which may be the sealing blade. For this machine a rotor design is shown which does not have ports.

The inlet and delivery working spaces 11 and 10 are in full and continuous communication with the duct openings in the casings 16 and 19 via the rotating duct 17 and the delivery casing 18. The 'anchor' type rotor comprises a bar 3 supporting at one end the lobe 4 and at the other end the sealing plate 7 and being mounted on the driving shaft. This bar is narrow, so that it does not form an end wall to the working spaces. The thickness of this bar may be increased locally as weight to correct the dynamic balance of the lobes and sealing plates, as shown at 20 in FIGS. 1 and 2.

Each blade 8 is mounted on a shaft passing through the back plate 15 and provided with a gear 21 which engages an intermediate gear 22 itself engaging a gear 23 on the driving shaft of the machine. The ratios of the gears are so chosen that each blade makes one revolution for each two revolutions of the driving shaft. Other forms of reduction gear may be used to obtain this drive ratio.

The machine can be run as a compressor, as a displacing or metering device or as a motor. The fluid flow may be reversed for a given rotation by turning the rotating duct 17 by 180° relative to the rotor.

I claim:

1. A fluid compressing, displacing or expanding machine comprising: a stationary casing having a cylindrical bore with a perpendicular end face, said casing having inlet and delivery openings disposed on the exterior thereof;

a plurality of blades mounted intermediate their ends within said bore in said casing for rotation about fixed axes parallel to the axis of said bore and spaced from one another circularly about the bore axis;

stationary pacing pieces disposed intermediate adjacent blades on the same radius as the axis of rotation of said blades;

a rotor rotatably mounted in said casing and being co-axial with said bore, said rotor having a pair of radially aligned lobes disposed on one side of the rotor axis;

an outer one of said lobes being disposed closely adjacent the surface of said bore in said casing and an inner one of said lobes terminating in a sealing hub disposed on the opposite side of the rotor axis from said lobes, said lobes being spaced apart from one another to permit widthwise passage of each blade and each stationary spacing piece as said rotor rotates;

drive means associated with said rotor and said blades for turning said blades about their axis at half the speed of said rotor, as said rotor rotates, from a radial direction in said bore to a direction at

right angles to the radius of said bore on the side of said rotor having lobes to provide a seal between the surface of said cylindrical bore and said sealing hub when in the former direction, and to allow said blades to pass between said lobes when in the latter direction;

a plate mounted upon said rotor on the side of the axis thereof opposite to said lobes and at right angles to said axis which makes sealing clearance with the ends of said blades when each blade is in its radial direction relative to the axis of said bore in said casing; and

passageways being rotatable with said rotor for the intake and delivery of fluid at opposite sides of said lobes and communicating with said inlet and delivery openings on the exterior of said casing.

2. A machine as claimed in claim 1, wherein said blades are parallel sided with a thickness to width ratio in the range of $0.4/N$ to $0.9/N$ where N is the number of blades and the inner surface of said casing is cylindrical throughout.

3. A machine as claimed in claim 1, in which the ends of said blades are mounted in bearings supported by a ring fixed in spaced relation within said casing.

4. A machine as claimed in claim 2, in which the tips of said blades are made to a radius larger than half the blade width.
